TAKE-UP DEVICE FOR FLEXIBLE CONDUCTORS

Albert McKesson, Chicago, Ill.

Application September 24, 1937, Serial No. 165,467

8 Claims. (Cl. 248—51)

This invention relates to take-up devices designed mainly for use in connection with electric appliances for taking up the slack in the flexible electric conductors when such appliances are in use.

Electric appliances, such as flat irons and other hand tools, are commonly provided with flexible conductors or cords of sufficient length to permit free movement of the appliance over the work or to its different points of application. The slack in the cord is often a source of annoyance to the operator because it permits the cord to drag along the working surface, gets in the way of the tool, and thus interferes with the work and sometimes damages the cord and the work.

In devices of this character it has been customary to provide a bracket or stand that may be clamped at its lower end on an edge of the ironing board or other work support and at its upper end pivotally supports an extensible spring coil that forms a sheath for the cord, this extensible and contractile sheath operating automatically to prevent the formation of slack in the cord as the tool is moved from and toward the supporting bracket.

It is also customary in devices of this character to form the flexible sheath in two endwise connected sections, the rear section being comparatively long and of light, easily stretchable wire, and the forward section being comparatively short and of considerably stiffer and heavier wire.

A typical example of a take-up device answering the above description is disclosed in my former Patent No. 1,943,134 dated January 9, 1934.

Among the objects of the present invention are, first, to provide an improved pivotal mounting of the sheath on its stationary support, which will afford a practically universal joint readily permitting up and down as well as horizontal swing of the cord and its sheath and will prevent accidental detachment especially under up and down swinging movement; second, to provide a substantially improved take-up device for flexible conductors that can be made and sold at less cost than such conductors now known and on the market.

Still other objects and attendant advantages of the present improvement will be apparent to persons familiar with devices of this character from the following detailed description taken in connection with the accompanying drawing in which I have illustrated an illustrative embodiment of the invention and wherein—

Fig. 1 is a perspective view of the device, also showing an electric flat iron and ironing board in dotted outline.

Fig. 2 is an enlarged view partly in section and partly in elevation and broken out between its ends, of the device and the upper portion of the support.

Fig. 3 is a fragmentary view showing in full lines an upwardly swung position of the rear end of the sheath and the portion of the cord lying therein, and in dotted lines a horizontal position of said parts, and

Fig. 4 is an end elevation as viewed from the left of Fig. 2, with the cord omitted.

In the embodiment of the invention herein illustrated, the device is shown as an automatic take-up for the flexible electric conductor cord of a flat iron 10 operating on an ironing board 11. The heating current is supplied to the iron through a flexible cord or conductor 12 having a plug 13 at one end for attachment to the customary socket and having a plug 14 at its other end for attachment to the iron 10.

The conductor cord 12 extends through a flexible and extensible sheath which, in the instance shown, consists of three endwise connected coil spring sections, namely, a main intermediate section 15 of considerable length and a high degree of stretchability, a rear section 16 of heavier and stiffer wire formed with a flaring rear end 16' and a forward section 17, also of heavier and stiffer wire, the forward end of which is attached to the plug 14. The manner and means of connecting these sections will be described later.

The rear section 16 of the sheath is pivotally supported on an upright bracket which is structurally closely similar to that disclosed in my former Patent 1,943,134, and comprises a clamp 18 adapted to engage with an edge of the board 11 and having on its upper end a curled portion 19 and a post 20 having its lower end bent at a right angle and entered in the curled portion 19 of the bracket as a bearing, so that the post 20, when not in use, can be folded down on and crosswise of the board 11 as shown in dotted lines in Fig. 1.

The upper end of the post 20 is shaped to provide a narrow annular lip 21, best shown in Fig. 2. The outer end coil of the flaring section 16' of the sheath is continued as best shown in Fig. 4 to form a small auxiliary coil 22 whose axis is at a right angle to the axis of the main coil or sheath. This coil 22 underlies the flaring section 16' and encircles the upper end portion of the post 20 with capacity of rotation on the lat-

ter. In assembling, the post 20 can be pushed through the coil 22 from beneath, the limbs of the coil spreading sufficiently to permit passage of the lip 21, and, of course, the coil 22 is prevented from dropping or sliding down the post 20 by reason of its integral connection to the end section 16 of the main sheath coil. Where, as in the construction of my former patent above identified, the pivotal connection with the post 20 was through a pin entering a socket in the upper end of the post, the pin would sometimes jump out of its socket thus breaking the connection under an upward swinging movement of the conductor cord and its sheath. In the present construction this cannot happen, since the lip 21 forms a stop that arrests the upward movement of the coil 22 when the sheath is swung upwardly as clearly shown in full line position, Fig. 3. However, by grasping the coil 16 with one hand 20 and the post 20 with the other and pulling them apart, the post and coil 22 can be separated.

Referring now to the means herein shown for connecting or coupling the meeting ends of the sections of the sheath, these meeting ends are connected by screwing one onto the other so that the coils interengage, the outer coils being seated on and between the inner coils, as clearly shown in Fig. 2. One practical way of effecting this is to mount the coils such as 16 or 17 on a rapidly 30 rotating mandrel. The meeting end of the coil 15 is then held against rotation and simultaneously pressed against the end of the rotating coil, whereby the two are screwed together into relatively overlapping and internested engagement. Before this is done, however, a sleeve such as 23 is slipped over the coil 15, and after the end portions of the two coils have thus been 35 interengaged, the sleeve is slipped back over the relatively overlapping coils, and is then punch 40 pricked at diametrically opposite points to form on the internal surface of the sleeve small teeth 24 that bite into the nested coils, and thus prevent endwise displacement of the sleeve, which latter serves to prevent any springing of the 45 outer coil away from the inner coil. This forms a very simple, strong and secure connection or coupling, and may be used to connect the intermediate section 15 to both of the end sections 16 and 17.

50 Although but one specific embodiment of this invention has been herein shown and described, it will be understood that details of the construction shown may be altered without departing from the spirit and principle of the invention as 55 defined by the following claims.

I claim:

1. In a device of the class described, the combination with a cord, a coil spring sheath for said cord, and a supporting bracket, of means for swiveling said sheath on said bracket consisting of an auxiliary coil continuous with said sheath encircling and rotatable on said bracket. 5

2. In a device of the class described, the combination with a cord, a coil spring sheath for said cord, and a supporting bracket, of means for swiveling said sheath on said bracket consisting of an auxiliary coil continuous with and 10 extending axially at an angle to said sheath encircling and rotatable on said bracket.

3. In a device of the class described, the combination with a cord, a coil spring sheath for said 15 cord, and a supporting post, of means for swiveling said sheath on said post consisting of an auxiliary coil continuous with one end of said sheath and extending axially at a right angle to the latter and embracing and rotatable on the 20 upper end portion of said post.

4. In a device of the class described, the combination with a cord, a coil spring sheath for said cord, and a supporting post, of means for swiveling said sheath on said post consisting of 25 an auxiliary coil continuous with one end of said sheath and extending axially at a right angle to the latter and embracing and rotatable on the upper end portion of said post, and means for locking said auxiliary coil against displacement 30 from said post under swinging movements of said sheath.

5. A specific embodiment of claim 4 wherein the coil locking means consists of an annular lip 35 on the upper end of the post sufficiently narrow to be pushed through the coil but forming a stop to prevent displacement of the coil from the post under swinging movements of the sheath. 45

6. In a device of the class described, the combination with a cord, of a coil spring sheath for 40 said cord formed with a flaring end, a supporting post, and means for swiveling said sheath on said post consisting of an auxiliary coil continuous with the outermost coil of said flaring end encircling and rotatable on said post. 50

7. A specific embodiment of claim 6 wherein the auxiliary coil extends axially at a right angle to the axis of said flaring end.

8. A specific embodiment of claim 6 wherein the auxiliary coil extends axially at a right angle 55 to the axis of said flaring end, and the post has a narrow annular lip above the coil forming a stop to prevent displacement of the latter from the post under swinging movements of the sheath.

ALBERT MCKESSON.
